(57) **CLAIM**

The ornamental design for a drinkware vessel as shown and described.

DESCRIPTION

FIG. 1 is a perspective view of the drinkware vessel; FIG. 2 is a front elevational view of the drinkware vessel of FIG. 1;

FIG. 3 is a rear elevational view of the drinkware vessel of FIG. 1;

FIG. 4 is a right side elevational view of the drinkware vessel of FIG. 1;

FIG. 5 is a left side elevational view of the drinkware vessel of FIG. 1;

FIG. 6 is a top plan view of the drinkware vessel of FIG. 1; FIG. 7 is a bottom plan view of the drinkware vessel of FIG. 1; and,

FIG. 8 is a cross-sectional view of the drinkware vessel taken through the line 8-8 in FIG. 6.
The broken lines shown in the drawings illustrate portions of the drinkware vessel that form no part of the claimed design.

1 Claim, 8 Drawing Sheets
